FISHING LURE

Francis E. Morrell, 243 Dollison St.,
Eureka, Calif. 95501

Filed Jan. 24, 1974, Ser. No. 436,118

Term of patent 14 years

Int. Cl. D22—05

U.S. Cl. D22—27

FIG. 2

FIG. 3

FIG. 6

FIG. 7

FIG. 4

FIG. 1

FIG. 5

FIG. 1 is a perspective view of a fishing lure embracing my new and ornamental design;

FIG. 2 is a front elevation of the article depicted in FIG. 1;

FIG. 3 is a back elevation view thereof;

FIG. 4 is a side elevation view directed to one side of the above-described article embracing my invention;

FIG. 5 is a side elevation view from the other side thereof;

FIG. 6 is a bottom plan view of the device shown in FIG. 1 embracing my invention; and

FIG. 7 is a top plan view thereof.
The broken lines are for illustrative purposes only.

I claim:

The ornamental design for a fishing lure, as shown and described.
